US0D1098285S

(12) **United States Design Patent** (10) **Patent No.:** **US D1,098,285 S**
(45) **Date of Patent:** **** Oct. 14, 2025**

(54) **REUSABLE WATER BALLOON**

(71) Applicant: **SHENZHEN HUAMINGJUN RUBBER CO., LTD**, Shenzhen (CN)

(72) Inventor: **Hongjun Zhang**, Shenzhen (CN)

(73) Assignee: **SHENZHEN HUAMINGJUN RUBBER CO., LTD**, Shenzhen (CN)

(**) Term: **15 Years**

(21) Appl. No.: **29/852,529**

(22) Filed: **Sep. 7, 2022**

(30) **Foreign Application Priority Data**

Jun. 24, 2022 (CN) 202230394924.X

(51) **LOC (15) Cl.** **21-01**

(52) **U.S. Cl.** ..... **USPC** **D21/572; D21/440**

(58) **Field of Classification Search**

USPC D21/436, 439, 440, 441, 443, 444, 445, D21/446, 453, 454, 455, 713; D12/323, D12/325; D30/160

CPC A63H 27/005; A63H 27/004; A63H 27/14; A63H 17/006; A63H 33/18; F41F 3/04; F41F 7/00
